UNITED STATES PATENT OFFICE.

DAVID BEHRSING AND CLARENCE A. GODSHALK, OF PHILADELPHIA, PENNSYLVANIA, ASSIGNORS TO FOX AUTOMOTIVE PRODUCTS CORPORATION, OF PHILADELPHIA, PENNSYLVANIA, A CORPORATION OF DELAWARE.

PUSH-BUTTON ELECTRIC-CIRCUIT MAKER AND BREAKER.

Application filed July 13, 1922. Serial No. 574,844.

To all whom it may concern:

Be it known that we, DAVID BEHRSING and CLARENCE A. GODSHALK, citizens of the United States, residing at Philadelphia, in the county of Philadelphia and State of Pennsylvania, have invented certain new and useful Improvements in Push-Button Electric-Circuit Makers and Breakers, of which the following is a specification.

10 Our invention relates to electric circuit makers and breakers, particularly to those of the push button type such as are employed upon motor vehicles for controlling the electric circuit by which the horn or other signalling device is operated. It has for its object to produce a housing for the circuit controlling parts of such a device, that is adapted to be easily applied and supported in immediate proximity to the steering wheel thereof.

20 In the accompanying drawings—

Figure 1 is an elevation of a horn button circuit controlling device embodying our improvements.

25 Fig. 2 is a vertical sectional view thereof.

Fig. 3 is a bottom plan view of the housing, detached.

30 In the drawings, 2 designates either the steering post of an automobile, or the short stub shaft that, in some makes of cars, is employed as an extension of the steering post or shaft. To this part is secured the steering wheel 3, which is held in place by a nut 4, the latter being secured to the reduced screw-threaded portion, 5, of the post or shaft 2. The parts thus far referred to 35 may be of usual or preferred construction. The nut 4 is provided with an extension 6, preferably of less size, in diameter, than the nut, at the base of which is a circumferential recess 7. The extension 6 is round in cross section and its upper portion is formed with a beveled or inclined face 8 just above the recess 7, and expanding 40 downwardly or toward the recess.

45 9 is a housing, preferably formed of thin metal, in which are located the circuit making and breaking devices. It is round in cross section, and is provided at its lower end with an inturned flange 10 adapted to enter the recess 7. The flange is cut in one or more places as indicated at 17, thus making it elastic and permitting the end of the

housing to be sprung over the tapering extension 6 of the nut. 55

The housing is also provided, at its upper end, with an inturned flange 11, that serves to hold in place the horn button 12, which is the part of the circuit controlling mechanism that is exposed and touched by the driver of the car whenever he wishes to sound his horn.

13 designates the contact mechanism located within the housing 9 and controlled by the horn button 12. This may be of any usual or preferred construction and is therefore not shown in detail. 14 designates the insulating base carrying the terminals and the contact-making parts of the device, it being located entirely within the housing 9, and preferably resting upon the upper edge of the extension 6 of the nut. The lower portion, 15, of the housing is preferably flaring, while the upper portion, 16, is cylindrical. These two parts join at approximately the plane in which is located the upper surface of the insulating base 14, when the parts are properly assembled. 75

25 The housing 9 is easily formed, and serves to enclose and protect the parts of the circuit maker and breaker. It may be easily and quickly applied to the nut 4 by merely pressing its lower expandable end over the flaring extension 6 of the nut. The housing may be separated from the nut by 30 tilting it bodily so that the flange 10 is sprung out of the recess 7. 80

35 It will be seen that while the housing is securely supported above the nut 4 it does not cover the latter, which is left free so 35 that it may be engaged by a wrench should it be desirable to tighten the nut or remove it. This may be done without injuring or distorting in any way the housing or necessitating its removal before the wrench 40 is applied. 95

45 What we claim and desire to secure by Letters Patent is:

1. The combination with a circuit making-and-breaking device having an exposed push button, of a housing therefor having an expandable, resilient inturned flange, and a support having a recess with which the said flange of the housing engages. 100

2. The combination of a nut at the end 105 of the steering post or shaft of an auto-

mobile, formed with an extension, at the base of which is a circumferential recess, a housing of shell-like form provided with inturned flanges at its opposite ends, and a circuit making-and-breaking device within the housing having an exposed button held in place by the flange at one end of the

housing, the flange at the other end being resilient and expandible and adapted to engage with the recess in the nut to hold the housing secured thereto.

DAVID BEHRSING.
CLARENCE A. GODSHALK.
